H. G. LEVY

ELECTRIC HAIR DRIER

Filed Jan. 17, 1928

FIG. 1.

FIG. 2.

INVENTOR:

H. G. LEVY

BY *White, Prost & Fagan*

ATTORNEYS.

UNITED STATES PATENT OFFICE.

HENRI G. LEVY, OF SAN FRANCISCO, CALIFORNIA, ASSIGNOR TO THE ELECTRIC MANUFACTURING COMPANY, OF SAN FRANCISCO, CALIFORNIA, A COPARTNERSHIP CONSISTING OF HENRI G. LEVY AND MONS ABRAMSON.

DESIGN FOR AN ELECTRIC HAIR DRIER.

Application filed January 17, 1928. Serial No. 24,906. Term of patent $3\frac{1}{2}$ years.

To all whom it may concern:

Be it known that I, HENRI G. LEVY, a citizen of the United States, and a resident of the city and county of San Francisco and State of California, have invented a new, original, and ornamental Design for an Electric Hair Drier, of which the following is a specification, reference being had to the accompanying drawing, forming part thereof.

Referring to the drawing:—

Figure 1 is a side elevation, and

Figure 2 is a front elevation of an electric hair drier embodying my design.

I claim:

The ornamental design for an electric hair drier, as shown.

HENRI G. LEVY.
